DESIGN FOR A WELDING ELECTRODE HOLDER

Frank R. Smith, Los Angeles, Calif.

Application March 10, 1944, Serial No. 112,858

Term of patent 14 years

(Cl. D26—1)

To all whom it may concern:

Be it known that I, Frank R. Smith, a citizen of the United States, residing in Los Angeles, in the county of Los Angeles and State of California, have invented a new, original, and ornamental Design for a Welding Electrode Holder, of which the following is a specification, reference being had to the accompanying drawing, forming part thereof.

Fig. 1 is a perspective view of a welding electrode holder, showing my new design.

Fig. 2 is a top plan view.

Fig. 3 is a side elevational view.

Fig. 4 is an end view, looking toward the right in Fig. 3.

Fig. 5 is an end view, looking toward the left in Fig. 3.

I claim:

The ornamental design for a welding electrode holder, substantially as shown.

FRANK R. SMITH.
